US00D690837S

(12) **United States Design Patent**
Mugge et al.

(10) **Patent No.:** US D690,837 S
(45) **Date of Patent:** ** Oct. 1, 2013

(54) **MOLDED SURFACE OF A CONCRETE PRODUCT**

819,055 A 5/1906 Fisher
824,235 A 6/1906 Damon
838,278 A 12/1906 Schwartz
1,086,975 A 2/1914 Aaronson
1,166,312 A 12/1915 Barten
1,564,490 A 12/1925 Parkhurst
1,574,125 A 2/1926 Sharpe
1,596,165 A 8/1926 Evans

(71) Applicant: **Anchor Wall Systems, Inc.**,
Minnetonka, MN (US)

(72) Inventors: **Jimmie L. Mugge**, Inver Grove Heights,
MN (US); **Robert Brian Burnquist**,
Chaska, MN (US); **Robert Joel Wolter**,
Chaska, MN (US)

(73) Assignee: **Anchor Wall Systems, Inc.**,
Minnetonka, MN (US)

(**) Term: **14 Years**

(21) Appl. No.: **29/442,277**

(22) Filed: **Jan. 18, 2013**

Related U.S. Application Data

(62) Division of application No. 29/373,660, filed on May 5, 2011, now Pat. No. Des. 678,552.

(57) **CLAIM**

The ornamental design for molded surface of a concrete product, as shown and described.

DESCRIPTION

FIG. 1 is a front perspective view of a molded surface of a concrete product;

FIG. 2 is a front view of FIG. 1;

FIG. 3 is a right side view of FIG. 1;

FIG. 4 is a left side view of FIG. 1;

FIG. 5 is a top view of FIG. 1; and,

FIG. 6 is a bottom view of FIG. 1.

The broken lines in the drawing views are included for the purpose of illustrating portions of the molded surface of a concrete product that form no part of the claimed design.

1 Claim, 6 Drawing Sheets
